UNITED STATES PATENT OFFICE

2,370,353

CENTRIFUGAL SEPARATOR OR CLARIFIER

Andrew F. Howe, University City, Mo.

Application September 19, 1940, Serial No. 357,348

2 Claims. (Cl. 210—69)

This invention has reference to a centrifugal separator or clarifier; and relates particularly to mechanisms for use in detaching solids and the like from fluids in which they are sustained or immersed, and thereby partially drying the solids.

Objects of the invention are to provide a machine comprising differentially rotating parts arranged to receive in a space between them the materials to be separated or clarified, and for effecting either a continuous or an intermittent flow and discharge of the separated and partially dried solids from one end of said space and the fluid from the other end of said space; to provide an improved and highly efficient mechanism for continuously rotating said parts; to arrange said parts at appropriate angles of inclination from a horizontal plane to control the movement of the solids toward the discharge outlet therefor at one end of said space; to provide means for regulating and controlling the movement of the solids toward the discharge outlet therefor; to provide means for controlling and regulating the velocity of centrifugal movement or flow of the solids into said space in order to prevent damage to or cutting of any of the parts by the solids contacting therewith; to provide improved valve means for opening and closing the space to effect intermittent discharge of the solids therefrom; to provide centrifugal actuators for said valve means for moving the same to closed position to prevent discharge of the solids from said space; to provide mechanism for intermittently opening said valve means to permit intermittent discharge of the solids from said space automatically and as an incident to operation of the machine; and to provide optionally operative devices for controlling said mechanism.

Various other objects and advantages of the invention will be apparent from the following description, reference being made to the annexed drawings, in which—

Fig. 1 is a vertical sectional view of a continuous centrifugal separator and the operating mechanism therefor embodying many of the features of the present invention.

Fig. 2 is an enlarged vertical sectional view of an automatic oil filter device embodied in the machine shown in Fig. 1.

Fig. 3 is an enlarged sectional view of the upper portion of the machine shown in Fig. 1.

Fig. 4 is a horizontal sectional view on the line 4—4 of Fig. 3, showing the means for controlling and regulating or retarding the centrifugal feed of sand and other heavy materials into the machine for processing operations.

Fig. 5 is a perspective view showing the parts of the screen bowl in separated relationship before being attached together.

Fig. 6 is a sectional view on the line 6—6 of Fig. 3.

Fig. 7 is a vertical sectional view of a solid bowl machine having a valve and centrifugal mechanism for closing the same.

Fig. 8 is an enlarged sectional view of the upper portion of the machine shown in Fig. 7, showing one form of mechanism for controlling the centrifugal devices provided to close the bottom valve.

Fig. 9 is a similar sectional view showing another form of said centrifugal devices.

Fig. 10 is a sectional view of a machine having two valves for alternately controlling discharge of solids from the solid bowl machine shown in Figs. 7 and 8.

The machine shown in Figs. 1 to 6, inclusive, is of the continuous flow type and comprises a tubular shaft 1 supported in bearings 2 and 3 for rotation about a vertical axis. A pulley 4 attached to the lower end of the shaft 1 is engaged by belts 5 driven by a pulley 6 constantly rotated by a motor 7. I have found that this type of driving mechanism for a continuous centrifugal drier is greatly superior to positive gear driving mechanisms and succeeds where such other mechanisms fail. The bearings 2 and 3 are mounted in a frame comprising a cylindrical portion 8 formed integral at its upper end with a substantially conical canopy 9. This frame 8—9 may be rigidly supported in a rigid frame structure 10.

The upper end of the shaft 1 is formed with an integral radial flange 11. An annular disc 12 is seated on the flange 11 and formed with an integral downwardly and outwardly inclined fluted peripheral portion 13 surrounding the upper end 40 of the canopy 9 and functioning as a guard to prevent foreign substances from passing into the upper end of the frame 8—9, and as a centrifugal impeller to cast off centrifugally any materials or substances that may contact therewith.

A bottom plate for the centrifugal cone and screen basket comprising an attaching portion 14 and an annular marginal conical portion 15 is seated upon the disc 12 and is rigidly attached to the flange 11 by screws 16 passing therethrough and through said disc and engaging in said flange 11. The screws 16 are removable and replaceable to permit needed removal and replacement of parts. The conical portion 15 of the bottom plate has a series of integral radial and circumferentially spaced arms or spokes 17 formed inte-

gral or rigid at their outer ends with a ring 18. The spaces between the arms or spokes 17 constitute passages for the solids or solid material discharged from the centrifugal mechanism in a substantially dry state because of the fact that a very large proportion of water and other liquid is separated from the solids by operation of the machine.

A conical screen basket 19 having therethrough a large number of elongated slots 20 extending generally in a circumferential direction has a radial supporting flange 21 seated upon the ring 18 and rigidly attached thereto by an annular series of removable and replaceable bolts or fasteners 22. The cone 19 constitutes a part of the screen basket and supports the remaining elements of said basket. A conical woven wire screen 23 (Fig. 5) is attached to the inner side of the cone 19; a relatively thin perforated plate 24 covers the entire inner surface of the woven screen 23, the holes 25 through said plate 24 being perpendicular or normal to the surfaces of said screen and, therefore, inclined outwardly and upwardly relative to the vertical axis of the cone and of the shaft 1. A relatively thin combined screen element and guard plate 26 is seated against the inner surface of the plate 24, and is formed with numerous horizontally elongated slots 27 through which water and other fluids may pass to the screen plate 24. The small inclined holes 25 permit the water and other fluids to pass therethrough; but, since the walls of said holes are inclined, centrifugally impelled solids are stopped by said plate 24 and do not pass in any substantial amounts through the holes 25. Some of the centrifugally impelled solids become lodged and retained temporarily within the slots 27 in the combined screen and guard plate 26. Because of the fact that the basket cone 19 is rigidly attached to the rotary tubular shaft 1, the entire screen basket comprising the cone 19, the screen 23, the plate 24, and the screen and guard plate 26, is rotated by and with said shaft. The upper margins of the screen 23 and plates 24 and 26 are rigidly attached to the upper end of the screen basket 19 by a clamp ring 28 and screws 29 (Fig. 3).

A rigid housing wall 30 forms a space 31 around the centrifugal screen cone and supports an inlet hopper 32 which extends downwardly into and through an opening in the upper end of the screen basket 19. The mixed liquids and solids are delivered into the machine through said inlet hopper either intermittently or continuously according to the nature of the materials and the purposes for which the machine is used.

A shaft 33 is mounted concentrically within the shaft 1 for rotation within bearings 34 and 35 mounted in said shaft 1 and permitting the shafts 1 and 33 to be rotated differentially. A gear 36 attached to the lower end of the shaft 1 meshes with a gear 37 attached to a shaft 38 journaled for rotation in bearings 39 about an axis parallel with the axis of the shafts 1 and 33. A gear 40 attached to the shaft 38 below the gear 37 meshes with a gear 41 attached to the shaft 38 below the gear 36. The dimensions of these gears 36, 37, 38 and 41 are such as to rotate the shaft 38 at any desired differential speed—either slower or faster—as compared with the speed of rotation of the shaft 1. In some instances, I have found it desirable to provide a differential of approximately 1000 revolutions of the shaft 1 to 990 revolutions of the shaft 38,

although this differential may be varied as desired.

A rigid leak-proof housing 42 encloses the differential gearing and also supports a bearing 43 for the extended end of the shaft 33 below the bearing 34. An oil container 44 is rigidly supported adjacent to the housing 42 and discharges oil through a tube 45 into the lower end of said housing to lubricate the gearing confined therein and the bearings 34 and 43. An oil pump 46 of known construction and operation is attached to the lower end of the shaft 38 and forces oil through a tube 47 opening into the cylindrical portion 8 above the bearing 3. The oil passing from the tube 47 lubricates the bearing 3 and passes downwardly therefrom to lubricate the bearing 2, and thence passes through a tube 48 into the container 44 and into a filter 49 in said container. Thus, the used oil is filtered before passing from the container 44 back into the housing 42 through the tube 45. The cap 50 of the container 44 is removable and replaceable in order to permit the filter 49 to be removed and replaced or cleaned as desired.

An inner trunco-conical member comprising a lower cone member 51 and an upper continuing cone member 52 is rigidly attached to and rotated by the upper end of the shaft 33 within the screen basket and separated from said basket by a conical space 53. A spiral series of flights 54 is attached to the inner cone within the space 53 and said flights are, in some instances, provided with elastic outer edges or rubbing surfaces 55 which rub or operate against the combined screen element and guard plate 26 because said flights are rotated differentially with respect to the screen basket. This differential movement of the flights rubbing against the plate 26 moves and stirs the solids temporarily lodged and retained within the slots 27, and causes said solids to move downwardly through the space 53 to ultimate discharge through the spaces between the spokes 17. In some instances, a conical or dome-shaped plate 56 is attached to the upper end of the inner cone (Fig. 1); or, if desired, a flat plate 57 (Fig. 3) may be attached to the upper end of said cone. Curved retarder flanges 58 (Fig. 4) are formed integral or rigid with the upper surface of the plate 56 or the plate 57, as the case may be, the outer ends of said flanges curving to form pockets 59 in the forward sides thereof to retard and delay speed of centrifugal movement of the materials discharged onto said plates through the inlet 32. The pockets 59 are formed by continuous rearward and forward curvature of the flanges 58. The materials are discharged slowly and without great centrifugal force from the pockets 59 into the space 53. By centrifugal action of the mechanism, the materials are thrown against the screen basket through which the liquids pass into the liquid receiving space 31. Wall structure 60 at the lower end of the space 31 forms a conduit to receive the liquids and conduct them to a suitable point of delivery and prevent them from passing downwardly to the solids discharged from the lower end of the space 53.

The solids pass from the lower end of the space 53 between the spokes 17 onto a rotary conical floor 61. The conical floor 61 is supported on rollers 62 and has its upper portion extending inwardly toward the stationary conical frame 8 in order to receive and conduct downwardly the solids passing from the space 53. An annular rack 63 is attached to the inner side of the conical

floor 61 and is engaged by a constantly rotating gear 84 attached to the upper end of a shaft 85. The shaft 85 is driven by any appropriate mechanism, and is preferably coordinated with the motor 1 so that the floor 61 will be rotated concurrently with the operation of the centrifugal mechanism.

The solids are discharged from a rotary conical conveyor or floor 61 onto the bottom 66 of a receiving chamber 67. A series of sweeper arms or flights 68 are attached to the lower peripheral portion of the conveyor floor 61 and sweep the solids along the floor 66 to a suitable opening (not shown) through which the solids are discharged from the chamber 67. The sweeper arms or flights 68 also tend to separate the solid particles or pieces and prevent cohesion thereof.

The forms of the invention shown in Figs. 7, 8, 9 and 10 are embodied in a continuous centrifugal self-cleaning separator and clarifier of the solid bowl type. One form of solid bowl machine is disclosed in my companion application Serial No. 129,144, filed March 5, 1937, patented October 22, 1940, No. 2,218,532. Said machine comprises a rotary solid bowl 69 rigidly attached by fasteners 70 to a support 71. The bowl 69 is above the support 71, and said support has numerous passages 72 therethrough for the downward discharge of solids from the bowl 69. The support 71 is rigidly and detachably secured to and supported by a flange 73 formed on the upper end of a tubular shaft 74 analogous to the shaft 1, already described. The shaft 74 is supported in bearings 75 and 76 for rotation about a vertical axis. A pulley 77 attached to the lower end of the shaft 74 is engaged by a belt or belts 78 operated by a pulley 79 constantly rotated by a motor 80. This driving mechanism for the shaft 74 is like that already described for driving the shaft 1 and possesses the same advantages. The bearings 75 and 76 are mounted in a rigid stationary frame including a cylindrical portion 81 enclosing and supporting the bearings 75 and 76 and formed integral or rigid with a substantially conical frame portion 82. This frame is rigidly mounted in a frame structure 83. By this mechanism the shaft 74 and the solid bowl 69 will be constantly rotated when the motor 80 is running.

A shaft 84 is mounted concentrically within the shaft 74 for rotation in bearings 85 and 86 which permit said shafts to be rotated differentially. A gear 87 attached to the lower end of the shaft 74 meshes with a gear 88 rigid on a shaft 89 journalled for rotation in bearings 80 about an axis parallel with the axis of the shafts 74 and 84. A gear 91 attached to the shaft 89 below the gear 88 engages a gear 92 secured to the shaft 84 below the gear 87. The relative dimensions of these gears are such as to rotate the shaft 84 at any desired differential speed with respect to the speed of rotation of the shaft 74. The differential of rotation as between these shafts may be varied as desired. A rigid housing 93 encloses the differential gearing and supports a bearing 94 for the extended lower end of the shaft 84.

A wall 95 is attached to the extended upper end of the shaft 84 beyond the upper end of the shaft 74 and within the solid bowl 69. A tube 96 rigid with the wall 95 constitutes a passage through which the mixed solids and liquids are conducted into the centrifugal mechanism for separation. A number of openings 97 in the lower end of the tube 96 permits the solids and liquids to flow or to be forced by centrifugal action

from within the tube 96 to the outside of said tube within the solid bowl 69. A conical series of inclined flights or agitators 98 is attached to the tube 96 and operate close to the inner surface of the solid bowl 69 to assist movement of the solids downwardly and the liquids upwardly for discharge from said bowl, substantially in the manner of my said Patent No. 2,218,532.

An annular space 99 is formed between the lower portion of the wall of the solid bowl 69 and the periphery of the bottom wall 95. The wall 95 is below the openings 97 and, for a short time, supports the solids and liquids until they are thrown outwardly by centrifugal action, assisted by the flanges 100 above the wall 95 and at the lower end of the tube 96. The agitator flights 98 extend downwardly through the annular space 99 and terminate near the lower end of the continuously rotating solid bowl 69.

20 Valve means comprising a plate 101 is provided for intermittently opening and closing the lower end of the bowl 69 to effect intermittent discharge of the solids from said bowl through the passages 72. A hub 102 formed integral with the plate 101 is mounted on the upper end of the shaft 84 for longitudinal sliding and relative turning movements. The hub 102 cooperates with the enclosed portion of the shaft 88 to form an oil chamber 103 rendered leak-proof at its upper and lower 30 ends by elastic gaskets or packing devices 104, preferably retained from longitudinal displacement and leaving the shaft 84 free to rotate while the plate 101 remains stationary, and permitting longitudinal sliding movements of said plate along the shaft 84.

35 The plate 101 is located between the support 71 and the lower end of the solid bowl 69, and is of greater diameter than the opening from the lower end of said bowl. An annular valve seat 105 is attached to the lower end of the bowl 69 for engagement by a sealing ring 106 attached to the plate 101. The plate 101 may be moved longitudinally along the shaft 84 to engage the sealing ring 106 with the valve seat 105 and thereby close the lower end of the solid bowl to prevent discharge of solids therefrom through the passages 72.

40 In the arrangement shown in Figs. 7 and 8, an annular series of centrifugal actuator weights 107 are mounted on pivots 108 carried by the support 71. The weights 107 are inwardly beyond the passages 72 and have arms 109 engaging against the underside of a bearing ring 110 in connection with the underside of the plate 101. 45 Because of the fact that the support 71 is continuously rotated when the motor 80 is running and the machine operating, the weights 107 are impelled outwardly by centrifugal force, as required to support the plate 101 in a position in which the seal 106 engages the valve seat 105 and thereby completely closes the lower end of the bowl 69 and prevents passage of any of the solids downwardly from said bowl through the discharge openings 72. The centrifugal actuators 107 will hold the valve device closed even against the pressure applied against the upper side of said valve device by the materials within the bowl 69 impelled by centrifugal force.

50 A support 111 (Fig. 7) is attached to the lower end of the housing 93. A cylinder 112 is attached to the lower extended end of the shaft 84 within the support 111. The shaft 84 is tubular and its lower end opens into the cylinder 112, and the upper end of said shaft has passages 113 opening

into the chamber 103. A series of tubes 114 form communication from the chamber 103 to a series of cylinders 115 attached to the support 71. Pistons 116 in the cylinders 115 have stems 117 engaging arms 118 extending inwardly from the upper ends of the centrifugal actuator weights 107. The cylinder 112, shaft 84, passages 113, tubes 114, and cylinders 115 contain oil or other hydraulic liquid whereby the pistons 116 may be moved and forced in a direction to move the centrifugal actuator weights 107 inwardly, leaving the valve plate 101 free for downward movement from the valve seat 105 to permit discharge of solids from the lower end of the bowl 69 through the passages 72. Each cylinder 115 may enclose a spring 119 to assist in quickly moving the piston 116 to actuate or disable the centrifugal weight 107 controlled by said piston. By this arrangement the valve plate 101 is caused to rotate with the solid bowl 69 instead of with the shaft 84, the ends of the chamber 103 being kept leak-proof by the sealing gaskets 104.

A piston 120 is mounted in the lower end of the cylinder 112, and has a rod 121 projecting downwardly through a packing 122 at the lower end of the support 111. The lower end of the cylinder 112 is rotatively mounted in a bearing 123 in the support 111. The lower end of the piston rod 121 has pin and slot connection 124 with a lever 125 mounted on a fulcrum 126 whereby the piston 120 may be moved upwardly to force the oil or other liquid against the lower ends of the pistons 116 to cause said pistons to disable the centrifugal actuators 107 and move them inwardly against the impulse of centrifugal force to permit the valve 101 to be opened by the pressure of the solids within the bowl 69. When the lever 125 is released, the centrifugal weights 107 will swing outwardly, forcing the liquid from the cylinders 115 through the tubes 114, chamber 103, and shaft 84, into the cylinder 112 to move the piston 120 downwardly.

The solids passing from the openings 72 are discharged onto a rotary conical floor 127 analogous to the rotary conical floor 81 and supported on rollers 128 carried by the frame 82 and centered by rollers 129, also carried by said frame. An annular rack 130 attached to the conical floor 127 meshes with a pinion 131 secured to the upper end of a rotary shaft 132. A gear 133 is attached to the lower end of the shaft 132 and meshes with a pinion 134 secured to a shaft 135 supported within the housing 93. A worm gear 136 attached to the shaft 135 meshes with a worm 137 on a shaft 138 rotatively supported within the housing 93. The shaft 138 is constantly rotated when the motor 88 is running by a pulley 139 attached to said shaft and engaged by the belts 78. An oil pump 140 is operated by the shaft 138 within the housing 93 to circulate oil in the manner explained in the description of Fig. 1.

The lever 125 may be manually operated, or mechanically operated at or after equal time intervals, as desired. As shown generally at the lower portion of Fig. 7, a lever 141 attached to a rotary shaft 142 may be equipped with a roller device 143 to engage and operate the lever 125 to raise the piston 120. A gear 144 attached to the shaft 142 meshes with a pinion 145 secured to a rotary shaft 146. The shaft 146 may be driven by a motor 147 in order to rotate the lever 141 to engage the roller 143 intermittently with the lever 125 and operate the same to raise the piston 120; and, during continued movement of

the lever 141, to pass the roller 143 beyond and out of engagement with the lever 125. When the roller 143 passes out of engagement with the lever 125, the pressure of the materials within the bowl 69 opens the valve 101 and permits flow of the solids from said bowl until the valve is again closed. The lever 125 is operated by the lever 141 once during each revolution of the shaft 142, and speed of rotation of the latter may be regulated and timed as desired in order to effect operation of the valve 101 at the desired time intervals.

The oil circulated by the pump 140 to lubricate the bearings 76 and 75 is returned to the housing 93 through a pipe 148. From the housing 93 the oil may pass into the support 111 through a passage 149 to lubricate the bearing 123.

The construction and arrangement of the parts of the machine shown in Fig. 9 are the same as the construction and arrangement of the parts shown in Figs. 7 and 8, with the exception of the means for operating the centrifugal actuators. In Fig. 9, the centrifugal actuators 150 supported on the pivots 151 have arms 152 engaging the bearing ring 110 in the manner that the arms 109 engage said bearing ring. The cylinders 153 enclose pistons 154 having rods 155 engaging levers 156. The levers 156 are supported on pivots 157 and have projections 158 engaging in frames 159 attached to the centrifugal actuators 150. When the pistons 154 are forced outwardly by the liquid entering the cylinders 153, the levers 156 are operated to move the centrifugal actuators 150 to ineffective positions against centrifugal impulse, leaving the valve 101 free to open. In other particulars, the mechanism shown in Fig. 9 is the same as that already described, and the same reference numerals are applied to like parts.

During operation of the machine, the solids discharged through the openings 72 onto the impeller cone 127 pass to a supporting floor 160 along which the solids are moved or swept and agitated by sweeper and stirrer arms 161. The solids are moved to a discharge outlet (not shown), and the agitation and movement thereof by the arms 161 effectively prevent cohesion and increase the drying effect of the machine.

The machine shown in Fig. 10, like the machines shown in Figs. 7 and 8, is generally designated a "solid bowl" machine because the bowl 69 is imperforate and does not function as a sieve or strainer to permit passage of liquid therethrough, but requires the liquids to pass from the bowl through the upper end thereof, as disclosed in my said Patent No. 2,218,532, dated October 22, 1940. The same reference numerals are applied to like parts in Figs. 7, 8 and 10. The machine shown in Fig. 10 comprises two valve devices for alternately and intermittently controlling discharge of solids from the bowl 69 instead of the single valve means 101 contained in the machine of Figs. 7 and 8.

As shown in Fig. 10, the agitator flights 98' terminate considerably above the valve seat 105, and are of less length than their analogs 98, to provide space for an annular valve seat 162 attached to the inner surface of the bowl 69 just below the ends of the agitator flights 98'. Valve means comprising a plate 163 is formed rigid or integral with the hub 162' analogous to the hub 102 previously described and arranged in the same relationship to like elements contained in the preceding form of the invention and having

the same reference numerals applied thereto as are applied to said parts in Figs. 7 and 8. The outer margin 164 of the valve plate 163 inclines upwardly and is of reduced thickness around its edge so as to make effective sealing contact with the valve seat 162 when the plate 163 is moved upwardly to its closed position.

The plate 163 is formed with an outer annular guiding member 165 concentric with the hub 162 and with the shaft 84. A valve plate 166 is 10 formed with an integral hub 167 mounted for sliding movements on the guide member 165 below the valve 163. A sealing ring 168 is attached to the upper surface of the valve plate 166 for engagement with the valve seat 165.

An annular series of rocker levers 169 are mounted for rocking movements on supports 170 attached to the plate 171 constituting a part of the rigid support 71 secured to the bowl 68. The tubes 114 that form communication from the chamber 103 to the series of cylinders 115, attached in this instance to the plate 171, pass through openings in the valve plate 163 so as to function in the manner before described to operate the centrifugal devices 107 by which the valve plate 166 is moved to its closed position.

In operation, the shafts 74 and 84 are continuously rotated at differential speeds by the mechanism shown in Fig. 7, and the valve 166 is alternately opened and closed by operation of the centrifugal actuators 107. When the valve 166 is closed, the valve 163 is opened and held open by the contents of the bowl 68 against the upper side thereof, which pressure is increased by centrifugal force. This permits the solids to pass the valve 163 into the space immediately above the valve 166. When fluid pressure is admitted into the cylinders 115, the centrifugal actuators 107 are moved to positions to permit the valve 166 to be opened by the pressure of the solid materials thereon, which is increased by centrifugal force. When the valve 166 is thus opened, the solids can pass out through the passages 72. Downward movement of the valve 166 in this manner operates the rocker levers 169 to raise the valve 163 to its closed position, and this alternate operation of these valves is repeated to discharge measured quantities of solids from the bowl 68 under control of the alternately and intermittently operated valves 163 and 166.

From the foregoing, it should be apparent that this invention comprises a practical mechanism capable of application to many uses. It has been used with a high degree of efficiency and satisfaction for the separation of various solids from liquids and substantially drying the solids passing through the machine. The desired angle of inclination of the screen basket 18, etc. shown in Fig. 1 has been found to be about 52° for dry-

ing sand and distillery slops and the like; about 60° for drying coal; and about 45° for drying pulp. The angle of inclination of the screen basket may be varied for different purposes and uses to attain best results as determined by experience. The term "angle of inclination" refers to the inclination with respect to the horizontal plane.

The machine may be varied in various other particulars than those specifically described and shown in the drawings without departure from the nature and principle of the invention. I contemplate such variations within the scope of equivalent limits as may be desired.

15 I claim:

1. In a centrifugal machine having a perforated outer conical element provided with a screen and a solid inner conical element forming between them a space for receiving mixed solids and liquids and having an inlet for supplying said mixed solids and liquids into said space and also having a downwardly directed opening for discharging said solids from said space, outer and inner coaxial shafts for rotating said outer and inner elements, respectively, and a housing wall around said outer conical element forming a space for receiving liquids separated from said solids; a substantially annular trunco-conical floor concentric with said shafts located below said space for receiving said solids discharged therefrom through said downwardly directed opening, connections covered and protected by said floor for rotating said outer shaft, gearing for rotating said inner shaft by said outer shaft, and gearing wholly covered and protected by said floor for rotating said floor by said connections.

2. In a centrifugal machine having an outer conical element and an inner element coaxial and cooperating with said outer element to form between them a space for receiving mixed solids and liquids and having an inlet for supplying said mixed solids and liquids into said space and also having a downwardly directed opening to discharge said solids from said space, a housing wall around said outer conical element forming a space for receiving liquid separated from said solids, and outer and inner coaxial shafts for rotating said outer and inner elements, respectively; a substantially annular trunco-conical floor concentric with said shafts located below said space for receiving said solids discharged downwardly therefrom through said downwardly directed opening, rollers covered by and supporting said floor for rotation, gearing covered by said floor for rotating the same during rotation of said outer and inner elements, a motor for operating said gearing, and connections driven by said motor for rotating said shafts.

ANDREW F. HOWE.
